UNITED STATES PATENT OFFICE

2,553,926

BLADE OSCILLATING MEANS FOR EARTH-
WORKING IMPLEMENTS

Per Lund, Oslo, Norway

Application December 31, 1947, Serial No. 795,062
In Sweden November 19, 1946Section 1, Public Law 690, August 8, 1946
Patent expires November 19, 1966

1 Claim. (Cl. 37—143)

1

This invention relates to machines for road and ground working as well as excavators and the like and its object is to increase the efficiency of such machines. The invention is principally characterized in that the working, particularly, excavating tools are adapted to be given a rotating, translatory movement in relation to the holder of the tool in such a way, that all points of the tool rotate in planes generally parallel with or perpendicular to the plane of working of the tool with respect to the surface of the ground. Through this rotating movement the tool acquires an oscillating motion in the direction of the advance of the tool with respect to the ground, whereby the working resistance acting upon the tool is decreased and the efficiency of the machine increased. The invention may with advantage be adapted for road planers and similar machines, where the tool, usually in the form of a bar or a blade, is driven by means of two or more crank-shafts parallel with each other, which are connected by crank arms with the tool at a corresponding number of points.

The invention is illustrated by the accompanying drawing, which diagrammatically shows the drawing means for a grader or similar tool.

Fig. 1 is a side elevation of the arrangement, and

Fig. 2 a plan view of same.

In the example shown the tool consists of a blade 1, which is formed of a piece of iron plate in the form of a bar and arranged to be advanced at an acute angle to the surface of the ground, as shown in Figure 1. According to the invention the blade is adapted to be given an oscillating movement by means of a number of crank shafts 2, 3, 4, 5, which are connected with the blade by means of crank arms 6 forming obtuse angles with the crank shafts and which consequently describe conical surfaces when rotating. The rods may be connected with the planer by means of ball joints 8, which are parallel with the crank shafts. All of the crank shafts and thereby the planer, also are supported by tool holding arms 7, and which are secured to the frame of the machine. The tool holding arms 7 have downwardly inclined forward extensions 7a which mount the forward crank shafts 2 and 4 at their lower ends, the inclination of these extensions determining the inclination of the blade 1. Bevel pinions 9 are mounted at the upper ends of the crank shafts 2, 3, 4, and 5, and it will be understood that a unitary drive means (not shown) is provided for these pinions.

As shown in Figure 2 the blade is carried by four crank shafts arranged in pairs at opposite ends of the machine. The crank arms are of equal length and adapted to rotate at equal speed,

5 at equal angles, and on phase, that is in such a way that the crank arms at all angle positions are located in crank shaft planes parallel with each other. Thereby the blade will be given a translatory movement, that is the front edge of the blade is moving parallel with itself, so that the blade, when advancing along the ground, will be given an oscillating movement in the direction it is being pushed, whereby the working 10 of the ground is facilitated.

15 In connection with certain types of machines, for instance ground breakers but also with road working machines, it may be useful to combine the rotation with translatory movement of the 20 blade in such a way, that all the points of the blade are rotating in planes, which are generally perpendicular to the working plane of the blade with respect to the surface of the ground. A blade of the kind shown in the drawing should then be adapted for rotation around horizontal shafts.

25 A machine of the type described above may be used with advantage even for the removal of ice and snow from the roads.

25 I claim:

30 In a road grader, a pair of crank shaft holders having horizontally positioned sections and downturned end sections at an obtuse angle thereto, a pair of crank shafts for each holder, each crank shaft having a vertically positioned section with the vertically positioned section of one crank shaft rotatably mounted in a bearing in the horizontal section of the crank shaft holder and the vertically positioned section of the other crank shaft rotatably mounted in a bearing in the 35 downturned section of the crank shaft holder each crank shaft having an outer section extending at an obtuse angle to the vertically positioned section, a cutting tool of generally plane configuration, and ball and socket joints connecting the outer ends of the crank shafts with the tool, whereby the cutting tool oscillates in parallelism with the downturned ends of the crank shaft holders.

PER LUND.
